UNITED STATES PATENT OFFICE

2,422,105

COOLING APPARATUS FOR HEAT-TREATED WORK USING AIR JETS

William Lehrer, Toledo, Ohio, assignor to Surface Combustion Corporation, Toledo, Ohio, a corporation of Ohio

Continuation of application Serial No. 489,567, June 3, 1943. This application October 19, 1945, Serial No. 623,242

6 Claims. (Cl. 34—225)

1

This application is a continuation of my application Serial No. 489,567 filed June 3, 1943.

The invention relates to heat treating furnaces of the type embodying an elongated cooling chamber for the controlled cooling of work after heating. Certain steels are advantageously quickly cooled from above to below the critical temperature; and it is the object of the invention to provide an improved cooling unit for thus initially quickly cooling the heated steel with a rapidly circulating gaseous cooling medium.

For a consideration of what I believe to be novel and my invention, attention is directed to the following specification and the claims appended thereto.

In the accompanying drawings,

Fig. 1 is a diagrammatic side elevation of a heat treating furnace embodying the present invention.

Fig. 2 is an enlarged vertical transverse section on line 2—2 of Fig. 1 with some parts more or less diagrammatically shown.

Fig. 3 is an enlarged vertical longitudinal section on line 3—3 of Fig. 1 with some parts more or less diagrammatically shown.

Fig. 4 is a fragmentary detail view on line 4—4 of Fig. 2.

Referring to Fig. 1, the heat treating furnace comprises a heating zone A, a quick cooling zone B, and a slow cooling zone C, in the order named. The gaseous cooling medium is of such composition as to constitute a protective atmosphere for the heated steel and this atmosphere will prevail throughout the length of the furnace.

In the case of elongated work such as tubes or sheets (diagrammatically indicated at W in Figs. 2 and 3), a roller hearth conveyor 5 will ordinarily be employed for supporting the work during its progress through the furnace. In the heating zone or chamber A, the heating means may comprise upper and lower rows of radiant tubes 10. To reduce heat transfer between the heating and quick cooling zones to a minimum, the connecting passage therebetween is made as restricted as possible consonant with passage of the work therethrough. A vertically adjustable door 8 permits the effective height of the passageway to be adjusted as conditions may require. Water cooled wall sections 6 and 7 are desirably provided between said zones.

The quick cooling zone or chamber B comprises a horizontally disposed upper wall 15, a horizontally disposed lower wall 16, and side walls 17 therebetween. The aim of the present invention is to provide improvements in means for forcibly

2

circulating relatively great volumes of gaseous cooling medium into and out of contact with the heated steel passing through the cooling chamber and withal to construct certain parts of the apparatus in such a way as to permit ready assembly of the various separate parts in the field with minimum trouble and expense.

In the present invention there is provided above the cooling chamber B a plenum chamber 18 comprised of the horizontal wall 15, side walls 35 and a top wall 28. There is also provided below the cooling chamber a plenum chamber 19 comprised of the horizontal wall 16, side walls 38 and a bottom wall 30. An upper blower 25 delivers gaseous cooling medium to the upper plenum chamber 18 and a blower 26 delivers the same kind of cooling medium to the lower plenum chamber 19.

Gaseous cooling medium from the upper plenum chamber 18 is blasted against the upper side of the work by a plurality of nozzles 20 which extend downwardly from the bottom of the plenum chamber and which extend crosswise of the cooling chamber whereby the gas jet from each nozzle 20 is in the form of a continuous sheet crosswise of the cooling chamber. A damper 22 above each nozzle 20 permits adjustment of blasting effect lengthwise of the cooling chamber.

Gaseous cooling medium from the lower plenum chamber 19 is blasted against the underside of the work by a plurality of nozzles 21 which extend upwardly from the top of the plenum chamber and which extend crosswise of the cooling chamber whereby the gas jet from each nozzle 21 is in the form of a continuous sheet crosswise of the cooling chamber. A damper 23 below each nozzle 21 permits adjustment of the blasting effect lengthwise of the cooling chamber.

The upper blower 25 and the upper plenum chamber 18 are interconnected by a conventional bolted flange connection 29; and the lower blower 26 and the lower plenum chamber 19 are likewise interconnected by a conventional bolted flange connection 31.

The joint between the top wall 28 of the upper plenum chamber and the side walls 35 is made gas-tight by a liquid seal comprising a liquid holding trough 36 which encircles the upper portion of the plenum chamber, thus permitting the top wall to be readily installed gas-tight in the field. The joint between the bottom wall 30 of the lower plenum chamber and the side walls 38 is made gas-tight by a liquid seal comprising a peripheral liquid holding trough 37 carried by

the bottom wall 30, thus permitting the latter to be readily installed gas-tight in the field.

The suction or intake side of the upper blower 25 is connected by a pair of return ducts 42 and 43 with the opposite sides of the upper portion of cooling chamber B; and the suction or intake side of the lower blower 26 is connected by a pair of return ducts 44 and 45 with the opposite sides of the lower portion of the said cooling chamber. This system of return ducts from the opposite sides of both the upper and lower portions of the cooling chamber is an important feature of the invention because the upper and lower portions of the cooling chamber are thereby made substantially independent of each other as regards circulation of the gaseous cooling medium.

At their intake ends, each of the return ducts is comprised of a horizontally extending row of exhaust ports each provided with a damper to control its effective inlet, thereby permitting the exhaust effect to be controlled lengthwise of the cooling chamber B. The exhaust ports for the upper half of the cooling chamber are indicated at 40 and those of the lower half at 41. The damper for the individual exhaust ports comprises an upright plate 52 fixedly secured to an upright turnable shaft 53 adapted to be held in adjusted position by a clamping nut on the shaft. In Fig. 4, the shaft projects through the lower adjacent wall 55 of the duct 42. For the lower dampers the shaft will project through the upper adjacent wall of the lower ducts 44 and 45.

Each of the upper return ducts 42 and 43 is made in upper and lower sections, and the joint therebetween is made gas-tight by a liquid seal comprising a liquid holding trough 60 which surrounds the lower section, thus permitting the sections to be readily connected gas-tight in the field; and each of the lower return ducts 44 and 45 is also made in upper and lower sections and the joint therebetween is likewise made gas-tight by a liquid seal comprising a liquid holding trough 61 which surrounds the lower section, thus permitting the sections to be readily connected gas-tight in the field.

In each of the four return ducts 42-45 there is provided a heat exchanger means for cooling the spent cooling medium, the means for the upper ducts being diagrammatically indicated at 63 and those for the lower ducts at 69. Water pipes leading to and from the individual heat exchangers are indicated at 50.

The recirculating rate of the upper blower 25 may be controlled by a master damper 58 and that of the lower blower 26 by a master damper 59. Make-up gas will ordinarily be supplied to the system at the intake side of the respective blowers.

What I claim as new and desire to secure by Letters Patent is:

1. In apparatus of the class described, the combination of wall means including top and bottom walls and right and left hand side walls forming a treating chamber wherein material on passing therethrough may be treated with gaseous treating medium, wall means including said top wall forming a first plenum chamber outside of said treating chamber for receiving a supply of said treating medium from means including a blower, a first set of right and left hand suction conduits leading from the suction side of said blower and communicating with the upper portion of said treating chamber through the right and left hand side walls thereof for withdrawing spent treating medium therefrom, wall means including said

bottom wall forming a second plenum chamber outside of said treating chamber for receiving a supply of said treating medium from means including a blower, a second set of right and left hand suction conduits leading from the suction side of the last mentioned blower and communicating with the lower portion of said treating chamber through the right and left hand side walls thereof for withdrawing spent treating gas therefrom, and nozzles extending into said treating chamber from the upper and lower plenum chambers for directing gaseous treating medium from the plenum chambers against the upper and lower sides, respectively, of the said material moving through the treating chamber.

2. In the combination as set forth in claim 1, each of said suction conduits having a joint between its ends and means comprising a liquid holding trough around each joint to make it gas-tight.

3. In apparatus of the class described, the combination of wall means including upper and lower walls and right and left hand side walls forming a treating chamber for material passing therethrough, wall means including a top wall and side walls above the said upper wall forming a plenum chamber for gaseous treating medium, a blower for delivering said treating medium to said plenum chamber, nozzle means for blasting

the top side of said material with gaseous treating medium from said plenum chamber, duct means leading from the treating chamber to the intake side of the blower for returning spent treating medium to the circuit, and means comprising a liquid holding trough encircling the upper portion of the plenum chamber to provide a gas-tight joint between the said top wall of the plenum chamber and the side walls thereof.

4. In apparatus of the class described, the combination of wall means including upper and lower walls and right and left hand side walls forming a treating chamber for material passing therethrough, wall means including a bottom wall and side walls below said lower wall forming a plenum chamber for gaseous treating medium, a blower for delivering said treating medium to said plenum chamber, nozzle means for blasting the underside of said material with gaseous treating medium from said plenum chamber, duct means leading from the treating chamber to the intake side of the blower for returning spent treating medium to the circuit, and means comprising a liquid holding trough encircling the lower portion of the plenum chamber to provide a gas-tight joint between the said bottom wall of the plenum chamber and the side walls thereof.

5. In apparatus of the class described, the combination of wall means including upper and lower walls and right and left hand side walls forming a treating chamber for material passing therethrough, means including a top wall and side walls above the said upper wall forming a plenum chamber for gaseous treating medium, a blower for delivering said treating medium to said plenum chamber, nozzle means for blasting the top side of said material with gaseous treating medium from said plenum chamber, means comprising a liquid holding trough encircling the upper portion of the plenum chamber to provide a gas-tight

joint between the said top wall of the plenum chamber and the side walls thereof, ducts leading upwardly from the opposite sides of the upper portion of the treating chamber to the intake side of said blower for returning spent treating medium to the circuit, each of said ducts com-

prising upper and lower sections, and means comprising a liquid holding trough surrounding each of said ducts at the joint between the sections thereof to make said joint gas-tight.

6. In apparatus of the class described, the combination of wall means including upper and lower walls and right and left hand side walls forming a treating chamber for material passing therethrough, wall means including a bottom wall and side walls below said lower wall forming a plenum chamber for gaseous treating medium, a blower for delivering said treating medium to said plenum chamber, nozzle means for blasting the underside of said material with gaseous treating medium from said plenum chamber, means comprising a liquid holding trough encircling the lower portion of the plenum chamber to provide a gas-tight joint between the said bottom wall of the plenum chamber and the side walls thereof, ducts leading downwardly from the opposite sides 20 of the lower portion of the treating chamber to the intake side of said blower for returning spent treating medium to the circuit, each of said ducts

comprising upper and lower sections, and means comprising a liquid holding trough surrounding each of said ducts at the joint between the sections thereof to make said joint gas-tight.
